SNOW FENCE

Filed Dec. 8, 1937

UNITED STATES PATENT OFFICE

2,161,450

SNOW FENCE

Carl P. Bohland, Watertown, S. Dak.

Application December 8, 1937, Serial No. 178,736

5 Claims. (Cl. 256—24)

My invention relates to snow fences and gate construction of a new and unique type involving permanent installation and easy manipulation of the fence to various heights and in series 5 of sections extending a considerable distance.

Among features of the device are, permanent construction and mounting, vertical adjustment according to snow condition and elevated positioning unobstructive to cultivation, etc., during 10 snowless seasons, unique sectional and connected fence sections and means for raising one section, as a gate, or a number of sections of fence simultaneously. Other objects and advantages are hereinafter fully set forth reference being 15 had to the accompanying drawing, in which:—

Fig. 1 is an elevation of a snow fence embodying my improved construction. Fig. 2 is an enlarged elevation of a fence standard with an auxiliary fence lifting boom and connected fence section. Fig. 3 is a right hand end elevation of 20 Fig. 2. Fig. 4 is a reduced scale view illustrating manner in which a series of the standards are set up on uneven ground. Fig. 5 is a reduced scale elevation of the end parts of a fence opposite from the manipulated end.

Referring to the drawing by reference letters and numerals, like characters designating corresponding parts in the various views, my snow fence comprises according to length of fence a 25 number of fence sections A connected end to end pivotally as at 6 in the upper bar of the fence. Each section A comprises preferably an upper rail bar 7 of sheet metal of inverted U-shape in cross section, a lower bar 8 also sheet metal 30 and of U-shape, a number of spaced parallel and vertical slats 9 fixed in said channel parts or bars, all of relatively light but sturdy construction. Bars 7—8 may be of other suitable construction.

For each fence section I provide a vertical guiding standard. Each standard comprises a pair of parallel upright posts 10, preferably pipe, and connected at their top ends as at 11 (see Figs. 2 and 3) their lower ends suitably im- 35 bedded and fixed as in a concrete base 12. The opening of said standard is in a plane at right angles to the direction of the fence to permit free, vertical movement of the fence therein by means presently to be described.

13 is a preferably concrete base in spaced aligned relation to one end of the fence and on which is secured an elongated frame 14 with a pivot 15 for a fence raising main boom 16 the outer movable end of which is pivotally connected at 6 40 to the upper corner part of the nearest fence

section A. 16A are a number of auxiliary booms, each pivotally mounted at 17 (with its lower end) in a bracket 18 fixed on a post base 12 adjacent the post. The outer end of each such boom is pivotally connected at 6 to a pair of 5 fence sections, said auxiliary booms adapted to be raised in unison with the main boom 16 and thus raise all the fence sections A simultaneously, boom 16 being provided with raising means which will presently be described.

The main boom raising means may comprise any suitable manipulating mechanism preferably a turnbuckle 19 engaging a threaded eye-bar 20 the eye of which is pivotally retained on a pin 21 in an upright frame or plate 22 on the boom 16. 25 31 is the other threaded eye-bar for the turnbuckle and pivotally connected at 23 to the rear end part of the frame 14 (see Fig. 1). Manipulation of the turnbuckle will of course raise or lower the boom to simultaneously and thereby 20 set the entire fence in any desired elevation, the respective fence sections being guided vertically in the openings of the standards 10, and the maximum raising movement will be such that the booms are positioned vertically all of 25 25 the booms brought to vertical position parallel to the standards 10 and the entire fence at this time being raised to maximum height (see dotted line position of booms and fence in Fig. 1).

Snow fences hitherto used can only build up 30 a snowdrift equal to the height of the fence, which in all cases is a fixed height. With the use of my device the fence can be raised as soon as the top of the snowdrift is at the same level as the top of the fence. By raising the fence the snow will build up or accumulate to a new level, 35 namely to the top of the snow fence in its raised position, and by repeating this procedure, as conditions demand, a drift of snow can be built up equal to the height of the top of the fence in its highest position. Vice-versa, in case of sudden thaws the snowdrift shrinks, the fence can be lowered to desired elevation so same will be ready for the next snow storm.

By proper manipulation, the snow which generally piles up on the road can be kept in the adjacent field and thereby keep the highway or road open for traffic. And, when the snow thaws in the spring the water from such drifts will be absorbed by the ground in the field, thus conserving moisture for agricultural purposes, and also keep water away from the road where it may do considerable damage.

This fence can also be used for cattle enclosure, or so-called corrals. By disconnecting the first 55

section of fence from the second section the said first section can be used as a gate. When used as a snow fence and same is located on ground used for agricultural purposes, the fence can be raised to full height and left there all summer without causing any inconvenience to farmers as plowing, seeding, harrowing and cultivating can be carried on, directly under the fence, which affords ample headroom. The snow fence, being of permanent installation is of course always ready for use even in case of unseasonable snows after farming activities have begun. In locations where sudden climatic changes may occur two tiers of fences may be used, a lower tier close to the ground all winter and an upper tier movable up and down as may be required. Such lower tier may be bolted to upper one and both raised for proper clearance for farm equipment.

Obviously this fence can also be used for a transverse fence in a field for conservation of moisture only; and it may be used for protection of groves of young fruit trees with several tiers of fence on the prevailing windward side of an orchard.

Another use for this fence is as in stock-yards, where swinging gates are objectionable. Sections of the fence can be installed which will serve as vertical lift gates. The main boom 16 may be raised quickly by any other suitable mechanical means or even an electric motor (not shown) subject to remote control.

The vertical lift type of gate above described is desirable further for the reason that no large area is required as when swinging gates are used and no snow clearance is first required as is the case in the use of horizontal swinging gates after a snowstorm.

To ease the lifting operation in my improved fence some or all of the auxiliary booms may be provided with an inclined booster device comprising simply an eyebolt 24 slidably insertible and retained in a pivot block 25 fixed at 26 to the boom and its eye end nearest the adjacent standard 10. 27 is a tension coil spring connecting said eye of bolt 24 and the post the other end of said spring connected as at 28 to the standard. 29 is a thumb screw on bolt 24 to regulate the tension of the booster spring. Initially, when the fence is to be raised from its lowest position the tension or booster brace 24-27 is of course greatest, and when the fence is raised from said initial position said means assist materially to raise the entire fence and continue to be thus useful until the spring loses its pull, at which time the booms have raised the fence considerably and the latter is easily manipulated toward its uppermost position.

Where a fence of this type is set up a considerable length of it is adjustable from one master boom, it being possible and practical to manipulate several hundred feet of fence. The all metal light construction eliminates loss by grass or brush fires.

In Fig. 4 a row of standards 10 are shown set up as required on uneven ground, it being understood that the standards must be perpendicular to the surface of the ground in which they are set. In Fig. 5 the end of the fence (opposite from the manipulated end) is shown and in which the last fence section A is guided vertically between a pair of diagonal braces (preferably pipe) 30 extending from the top of the last standard 10 to anchor blocks 12A or equivalent means.

It will now be clearly understood that my im-

proved fence, of considerable length may be easily raised or lowered by one man equipped with ordinary means for turning the turnbuckle, and the entire fence is held in any desired elevation by the simple manipulation described.

Modifications within the scope of the invention as herein disclosed, may be made without departing from the scope and spirit of my invention.

I claim:

1. A snow fence comprising a series of aligned fence sections each section comprising an upper horizontal rail and a corresponding lower rail and a number of suitably spaced upright slats retained in said rails, means for detachably connecting said rail sections end to end, a number of fence posts corresponding to the number of fence sections, said posts slotted to permit reciprocating vertical movement of the fence sections therein and means for actuating said fence in vertical plane and holding the entire fence in any desired elevation.

2. The structure specified in claim 1 in which said raising means comprises a lever oscillatable in vertical plane and connected with the upper rail of the first fence section, secondary levers oscillatable in unison with and by the lever, said secondary levers pivoted each near the base of a post and its outer end pivotally connected to the top rail of the fence in spaced relation to the post.

3. The structure specified in claim 1, in which said raising means comprises a lever oscillatable in vertical plane and connected with the upper rail of the first fence section, secondary levers oscillatable in unison with and by the said lever, said secondary levers pivoted each near the base of a post and its outer end pivotally connected to the top rail of the fence, and a flexible connection between each post and its adjacent secondary lever, said connection comprising means under spring tension and exerting an upward pull on the fence.

4. In fence construction of the class described, a number of aligned fence sections pivotally connected end to end, a series of fence posts comprising each a standard of two parallel fixed bars, a lever device mounted in common plane with the fence and adjacent one end thereof and the lever thereof comprising a fence raising boom connected at its end with the end part of the first fence section, auxiliary booms pivotally mounted and connected to the fence sections, each said latter boom corresponding in size to the said lever, means for raising and lowering said lever and the fence sections and the auxiliary booms simultaneously, said fence sections guidingly retained for vertical movement between the parallel bars of the said standards.

5. The structure specified in claim 4, in which said raising lever comprises in part an upright arm, a pair of threaded rods and a turnbuckle connecting same one rod pivotally connected to the free end of said upright arm, a fixed element in spaced relation to the pivoted part of the raising lever, the other threaded rod connected to said fixed element, a permanent base in which each said standard is mounted, a pivot block on said base adjacent the foot of the standard, each said auxiliary boom fulcrumed in a pivot block and extending in a plane parallel to the side of the fence and its free end pivotally connected to the upper rail of the fence, said raising lever and the auxiliary booms co-ordinated to oscillate in unison.

CARL P. BOHLAND.
